MECHANISM FOR LAYING OUT CURVES

Alfred F. Krumholz, Chicago, Ill.

Application May 28, 1932, Serial No. 614,145

29 Claims. (Cl. 33—27)

My invention relates to marking mechanism of a type for use in connection with laying out sheet metal work for the manufacture of pipes, and it has for its object the provision of a new and improved form and arrangement of parts by which a line for cutting may be marked across the end of a flat strip of sheet metal of such shape and in such position that when the sheet metal is bent into tubular form the line will define a plane at an angle with respect to the length of the pipe.

It is one of the objects of my invention to provide an improved mechanism of this type by which the angle of the plane as above described with respect to the length of the pipe may be controlled and varied as desired in connection with any desired diameter of pipe. To this end, it is one of the objects of my invention to provide one adjustable means for regulating the scope of the movement of the pencil in the direction corresponding to the circumference of the pipe, and to provide a second adjustable means for regulating the extent of movement of the pencil at right angles so as to control the angle of the plane defining the end of the finished pipe. It is one of the objects of my invention to provide improved adjustable means of the second named type of such form and arrangement that it can be adjusted to have the desired effect by a mechanical setting of one part by reference to a lineal scale and a mechanical setting of another part by reference to an angular scale without the necessity for any computation in connection therewith.

It is one of my objects to provide an improved arrangement of parts by which the marking pencil is given its movement in the direction corresponding to the circumference of the pipe by a single stroke of an arm travelling between predetermined fixed limits of movement whereby the end limits of the curve as marked may be clearly defined. It is one of the objects of my invention to provide an improved arrangement of this type in which means adjustable longitudinally of said arm is utilized for giving the pencil its said movement corresponding to the circumference of a pipe whereby any desired proportion of the full length of the arm may be made effective for this purpose so as to control the scope of such movement, a scale being preferably provided graduated to read in units of diameter whereby the adjustable part can be set on the arm by reference to the scale for a marking for a pipe of the desired size.

It is one of the objects of my invention to pro-

vide in a machine of this type improved adjustable guide means for assisting in the arrangement of the pieces of metal to be marked on the table of the machine.

It is one of the objects of my invention to provide an improved form and arrangement of driving and actuating means by which the movement of the pencil simultaneously in two different directions may be kept in timed relation so as to insure that the line of marking shall define a plane when the strip of metal is bent into tubular form as above set forth.

It is one of the objects of my invention to provide an improved arrangement by which the location of the seam of the finished pipe may be regulated readily with respect to the position of the plane defined by the line of marking.

It is another object of my invention to improve mechanisms of this type in sundry details hereinafter pointed out. The preferred means by which I have accomplished my several objects are illustrated in the drawings and are herein-after specifically described. That which I believe is set forth in the claims.

In the drawings,—

Fig. 1 is a top plan view of my improved mechanism, showing a strip of metal in position on the supporting table with a line of marking thereon, and showing in dotted lines two alternative lines of marking;

Figs. 2 and 3 are vertical sectional views taken substantially at lines 2—2 and 3—3 respectively of Fig. 1;

Fig. 4 is a top plan view of the mechanism for controlling the angle of the plane defined by the line of marking, being shown on an enlarged scale as compared with the showing of Fig. 1;

Figs. 5 and 6 are vertical sectional views taken at lines 5—5 and 6—6 respectively of Fig. 4;

Fig. 7 is a side face view of one corner portion of the frame.

Fig. 8 is a vertical sectional view taken at line 8—8 of Fig. 3 but on an enlarged scale;

Fig. 9 is a face view of an end portion of a strip of metal cut along the line laid out by my improved mechanism and ready to be bent into tubular form; and

Fig. 10 is a view of the part shown in Fig. 9 after it is bent into the form of a finished pipe.

Referring now to the several figures of the drawings, in which corresponding parts are indicated by the same reference characters, 15 indicates the top plate of a table supported by frame bars 16 and legs 17 as is best shown in Figs. 2

25

45

55

and 3. Along opposite sides of the table 15, I have provided rails 18 in spaced relation to the frame bars of the table, the oppositely disposed rails being in parallelism with each other for supporting the wheels 19 of a framework comprising side bars 20 connected together at one end by a frame bar 21, the frame bars 20 and 21 being provided with a platform 22 formed of sheet metal at one end of the framework. The arrangement is such that the framework and its platform 22 are movable longitudinally of the table to any desired adjusted position. The bar 20 at one side of the machine is provided with a bracket 23 (see Fig. 3) the outer end of which extends down opposite the rail 18, having a set screw 24 adjustably mounted therein so as to have releasable engagement with the rail for clamping the framework and platform in the desired adjusted position longitudinally of the table.

At one side of the table, I have provided a longitudinally extending guide bar 25 which is slidable transversely of itself and transversely of the table, means being provided for keeping the inner edge of the guide parallel with the rails 18. This means comprises a longitudinally extending shaft 26 rotatably mounted in arms 27 depending from the guide 25 and extending through slots 28 in the table top 15. As is best shown in Fig. 2, the shaft 26 is provided at opposite ends with pinions 29 which mesh with rack bars 30 on the bottom face of the table top, the arrangement being such that upon rotation of the shaft the guide bar 25 and the shaft 26 are moved evenly across the top face of the table so as to be kept at all times in parallelism with the rails 18, the end frame bars 16 being provided with slots 26a (see Fig. 3) for permitting such transverse movement of the shaft. A crank 31 is provided on the projecting end of the shaft 26 for giving the shaft the desired rotary movement.

Across the frame comprising the side bars 20, I have provided a bar 32 fixedly mounted in position at right angles to the inner edge of the guide bar 25, such bar 32 having a sleeve 33 slidably mounted thereon. An operating bar 34 is pivotally connected at one end with the sleeve 33, said bar 34 being slidably mounted at its opposite end portion in a sleeve 35 which is pivotally mounted upon a vertical axis so as to swing in a horizontal plane. In the construction shown, the sleeve 35 is pivotally connected to a sleeve 36 which is held in fixed position by a cross bar 37 extending between the frame bars 20.

Upon the bar 34, I have slidably mounted a sleeve 38 which has a pivotal connection with a slide block 39 which is slidably mounted upon a tubular bar 40 adjustably mounted in position by means of a long bolt 41. The bolt 41 is slideable longitudinally of the table in slots 42 in the side bars 20. The bar 40 is normally locked in the desired adjusted position with respect to the slots 42 by means of a nut 43 on one end of the bolt 41, the arrangement being such that when the nut 43 is tightened the tubular bar 40 is clamped between the side bars 20 of the frame. The bolt 41 is held against rotary movement by means of a bar 44 carried by the frame bar 20 and engaging the square head 45 of the bolt. The bolt 41 and tubular bar 40 are held against swinging movement with respect to the framework and the table by means of pinions 46 carried by the tubular bar 40 and meshing with rack bars 47 mounted on the inner faces of the frame bars 20.

The slide block 39 is provided with a tubular portion 48 arranged at a right angle to the slide bar 40, such tubular portion 48 serving as a slide-way for a rod 49 provided with a marking pencil 50 at one end and connected at its opposite end with suitable means for controlling the position of the rod longitudinally thereof.

The means for controlling the position of the rod 49 longitudinally of the table comprises a rotary member 51 in the form of a flat ring having a downwardly turned flange 52 at its inner edge, as is best shown in Fig. 5. The flange 52 extends downwardly through an opening in the platform 22, being held rotatably in position by means of a series of rollers 53 revolubly mounted upon the platform 22 and engaging a groove 54 in the outer face of the flange 52. In the construction shown three of such rollers 53 are employed arranged in spaced relation about the opening in the plate 22. At its lower end, the flange 52 is provided with a sprocket gear 55 fixedly mounted in position concentrically thereof.

Within the ring 51 and flange 52, I have rotatably mounted a turn table 56. This turn table 56 is held in adjusted position with respect to the ring 51 by means of a pin 57 extending through an opening in the turn table into engagement with any one of a plurality of openings 58 in the ring 51. The turn table 56 is provided with a centrally located slideway 59 thereacross with its central longitudinal line diametrically located. At right angles to the slideway 59, a second slideway 60 is provided, with its central longitudinal line arranged in radial position. The slot by which the slideway 60 is provided is comparatively shallow, as is best shown in Fig. 5, while the slot providing the slideway 59 is of considerable depth. In the arrangement shown, the slideway 59 is reinforced by ribs or arms 61 formed integrally with the table 56 and the slideways, the whole structure being preferably in the form of a casting.

Above the slideway 60, I have provided a slide block 62 which is held non-rotatably in position by means of a downwardly extending guide portion as is best shown in Fig. 6. The slide block is held in adjusted position longitudinally of the slideway 60 by means of a clamping bolt 64 extending upwardly through the radial slot 60 and through an opening in the slide block 62, being provided with a thumb nut 65 adjustably mounted thereon by means of screw threads for tightening the block against the turn table. In the construction shown, the head of the bolt 64 is squared for holding the bolt from rotating. Upon a boss 66 formed upon the slide block about the bolt 64, I have mounted a lever 67, such lever being held in position by the thumb nut 65 so as to be free to swing about the bolt when the nut 65 is tightened in position.

Upon the slide block 62, I have provided obliquely disposed arms 68, such arms in the construction shown being formed integrally with the slide block 62. A segment 69 is provided connecting the outer ends of the arms 68, such segment extending over the outer end portion of the lever 67 and being graduated in degrees about the axis of the lever. A handle 70 is provided on the outer end of the lever for swinging the lever to the desired angular position.

As is clearly shown in Figs. 4 and 5, the lever 67 is provided with a longitudinally extending slideway 71 the center line of which passes through the axis upon which the lever is mounted. 75

Within the slideways 59 and 71, I have provided a wrist pin 72 the portion of said pin located within the slideway 59 being squared in cross section so as to be held against rotary movement with respect to the turn table 56. Near its lower end, the wrist pin 72 is provided with an outwardly extending flange 73 which bears against the lower faces of the wall portions of the slideway 59. At its upper end, the wrist pin 72 is provided with screw threads for holding a thumb nut 74 adjustably in position, the arrangement being such that when the nut 74 is tightened against the top face of the lever 67 such lever is held against swinging movement and the pin 72 is held rigidly in position with respect to the turn table 56.

As is clearly shown in Fig. 4, the graduations upon the segment 69 are arranged to increase in value from a central point marked O toward both ends, the central O point being located in the extension of the central longitudinal line of the slot or slideway 69. At one side of the turn table, a further graduation is provided at 75, in the construction shown being graduated to read in inches, the arrangement being such that the index mark 76 on the arm 68 indicates by reference to the scale 75 the diameter of the circle which will be described by the bolt 64 upon a rotation of the turn table.

Below the turn table 56, I have provided a slide bar 77 located at right angles to the guide bar 25 and movable longitudinally of the table and of the guide bar. As is clearly shown in Fig. 3, the end portions of the slide bar 77 are slidably mounted between strips 78 and 79 mounted in spaced relation to each other on the inner faces of the side bars 20. At each end, the slide bar 77 is provided with a roller 80 rotatably mounted thereon in position to engage the inner face of the strip 78. The slide bar 77 is held against swinging movement with respect to the platform 22 by means of a tubular shaft 81 which is revolvably mounted upon the slide bar 77 by means of brackets 82, as is best shown in Fig. 8. At its ends, the shaft 81 is provided with pinions 83 which mesh with rack bars 84 mounted on the inner faces of the strips 79.

As is best shown in Fig. 5, the slide bar 77 is provided on its upper face with longitudinally extending strips 85 and 86 in spaced relation to each other for providing a slideway longitudinally of the slide bar for engagement with a roller 87 revolvably mounted on the lower end of the wrist pin 72. When the wrist pin 72 is adjusted to some point away from the axis of the turn table 56 as hereinafter described, upon a rotary movement of the turn table the wrist pin will be moved back and forth longitudinally of the table 15, serving through the roller 87 and the strips 85 and 86 to give the slide bar 77 a simple harmonic movement longitudinally of the table with the wrist pin. On the lower face of the slide bar 77 I have provided longitudinally extending strips 88 and 89 in spaced relation to each other so as to provide a slideway longitudinally of the slide bar parallel with the slideway provided by the strips 85 and 86. A roller 90 is mounted in the slideway provided by the strips 88 and 89, being held in position thereon by means of longitudinally extending plates 91. A pin or bolt 92 having an enlarged head portion at its upper end is revolvably mounted in the roller 90 so as to be supported thereby, the lower end of the pin 92 below the slideway having a pressed fit within an opening in a bracket 93 which in turn has a pressed

fit connection with the end of the rod 49. The arrangement is such that when the wrist pin 72 is moved back and forth longitudinally of the table as above described through the rotation of the turn table, the rod 49 and the pencil 56 are given a simple harmonic movement longitudinally of the table 15, such rod 49 being at the same time movable transversely of the table by reason of the sliding connection of the bracket 93 with the slide bar 77 through the medium of the roller 10 90, pin 92, and strips 88 and 89.

For giving the desired rotation to the turn table 56 and thus producing the desired movement of the rod 49 longitudinally of the table 15, and for at the same time giving the rod 49 a movement transversely of the table in timed relation, with such transverse movement of the rod 49 kept at all times proportional to the rotary movement of the turn table, I have provided an endless sprocket chain 94 extending about the sprocket gear 55 (see Fig. 5) and about sprocket pinions 95 and 96 shown diagrammatically in Fig. 1, the pinions 95 and 96 being so located as to maintain the pitch of the endless chain between such pinions parallel with the transverse bar 32 upon which the sleeve 33 is slidable. One of the links of the sprocket chain 94 is connected in any suitable manner with the sleeve 33 so as to cause the sleeve 33 to move transversely of the table therewith. The chain 94 is driven by means of a crank 97 connected by means of a short shaft 98 with the pinion 95, the crank 97 being provided with an operating handle 99 at its end. In the position of the parts as shown in Fig. 1, the crank 97 is at the limit of its movement in clockwise direction by reason of the engagement of the sleeve 33 with the side bar 20. With the parts in the position as shown in Fig. 1, when the crank 97 is rotated in counterclockwise direction the sleeve 33 will be given a movement transversely of the table and the bar 34 will be swung in clockwise direction in said Fig. 1, serving to move the slide block 39 and the rod 49 transversely of the table with the sleeve 33, and serving to give the turn table 56 a rotary movement in counterclockwise direction in said Fig. 1. The arrangement is such that when the sleeve 33 reaches the limit of its movement upon such counterclockwise rotation of the crank 97 in said Fig. 1, the turn table 56 will be in the same position as that shown in said Fig. 1, having been given a single complete revolution during the movement of the sleeve 33 across the table.

When it is desired to employ my improved mechanism for marking a strip of metal, the thumb nut 43 is loosened and the bar 40 and the bolt 41 are moved toward the left in Fig. 1 to the desired adjusted position for securing the desired length of stroke of the slide block 39 and the rod 49 transversely of the table. As the bar 40 is adjusted toward the left in said Fig. 1, the slide block 39 is moved inwardly and toward the left for shortening the length of the stroke of the slide block for each full stroke of the bar 34 and sleeve 33. In the construction shown, a graduated scale 100 is provided on one of the side bars 20 of the framework just above the slot 42 graduated with respect to the length of stroke of the slide block 39 and reading in inches of diameter. That is to say, the arrangement is such that when the bar 40 stands opposite the numeral 8 of the scale 100, for example, under such circumstances upon a full stroke of the bar 34 with the sleeve 33 the slide block 39 will be given a 75

movement transversely of the table equal to the circumference of a circle of a diameter of 8 inches. By a proper adjustment of the bar 40, the transverse movement of the slide block 39 and the rod 49 and pencil 50 can be made to equal the circumference of any desired size of circle corresponding to the diameter sizes indicated in inches by the scale 100, such scale 100 in the arrangement shown running from 3 to 12 so as to be capable of use for marking strips for finished pipes 3 to 12 inches in diameter.

With the bar 40 set in position to suit the desired dimension of pipe, and with a strip of sheet metal 101 in position on the table of such width as to be suitable for forming a pipe of a corresponding diameter, the thumb nut 65 by which the slide block 62 is secured in position is loosened so as to permit the slide block 62, and the lever 67, to be moved toward the left in Figs. 1, 2 and 4 so as to bring the index 76 opposite the numeral of the scale 75 corresponding to the diameter setting on the scale 100. The thumb nut 65 is then tightened for holding the block 62 in its adjusted position. The thumb nut 74 is then loosened and the lever 67 is swung to the desired angular position along the segment 69 corresponding to the desired angular formation of the end of the finished pipe. As the lever 67 swings about the segment 69, the wrist pin 72 is moved along the slideway 59 to the desired position in said slideway 59 so as to provide the proper eccentricity of the wrist pin with respect to the axis of the turn table for giving the rod 49 and the pencil 50 the desired movement back and forth at right angles to the transverse movement of the pencil corresponding to the circumference of the pipe.

In Fig. 10 which represents a finished cylindrical pipe section, the lines AB and AE define the angle by which the end of the pipe departs from the transverse, such line AE being equal to the diameter of the pipe. With the point C chosen to bisect the line AE, the line CE will, of course, represent the radius of the pipe, and with the line CD drawn parallel with AB the angle DCE will be equal to the angle BAE. It will be appreciated that the line BE represents the extent of movement of the pencil 50 longitudinally of the table by the crank arrangement comprising the wrist pin 72, with the mechanism set for marking the sheet metal strip 104 from which said pipe is made, and that the line DE represents half of such movement of the pencil longitudinally of the table. That is to say, half of the movement of the pencil longitudinally of the table for marking a line of cutting for the formation of a pipe of a given diameter having its end disposed at a given angle from the directly transverse position is represented by the altitude of a right triangle having its base of a length corresponding to the radius of such pipe and its hypotenuse disposed at the given angle from the base. It is thus clear that when the axis of the lever 67 is located at a radial distance of 6 inches from the axis of the turn table 56, corresponding to a diameter reading of "12" on the scale 75 for effecting a marking in connection with the formation of a 12 inch pipe, and when the lever 67 is set at an angle of 30° from the line joining the axis of the lever with the axis of the turn table, the wrist pin 72 will be automatically brought to a position at the required distance from the axis axis of the turn table for giving the pencil 50 the required movement longitudinally of the table for

the formation of the desired 12 inch pipe having the desired 30° end formation.

By my improved arrangement I am enabled to give the wrist pin 72 the required position of adjustment to suit a given diameter of pipe and a given angular formation of the end of the pipe by manual adjustments, comprising first a suitable setting of the lever 62 by reference to the lineal scale 75 to correspond to the diameter of the pipe to be formed and then a suitable angular setting of the lever by reference to the segment 69 to correspond to the desired angular formation of the end of the pipe to be formed.

With the rod 40 set at the desired adjustment by reference to the scale 100, with the slide block 15 62 also set at a corresponding position with reference to the scale 75, and with the lever 67 set in the desired angular position, the guide bar 25 is to be moved transversely of the table to bring its inner edge into contact with the point of the pencil 50. The strip of sheet metal 101 is then adjusted by hand into engagement with the guide 25, and the frame carrying the turn table 56 is adjusted longitudinally of the table and locked by the clamp 24, whereupon the mechanism is in condition for operation. With the parts in position as shown in Fig. 1, the crank 97 would be turned to the limit of its motion in counter-clockwise direction in said figure for producing a marking on said strip 101. When a fresh strip was substituted in place of the strip 101, the crank 97 would of course be rotated to the limit of its movement in the reverse direction. When it is desired to lay out a line of cutting for a pipe of a different diameter or of a different angular formation at its end, the machine can be very readily and quickly adjusted to suit such changed requirements, all of the adjustments being attained without the necessity for any computation, being effected merely by a setting of the three adjustable parts as above described to the desired scale positions. The arrangement is such that any intelligent workman can use the machine successfully without any difficulty whatever.

Whenever it is desired to change the position of the seam of the pipe, this can be effected by an adjustment of the turn table 56 with respect to the ring 51 by the use of the pin 57. That is to say, upon a withdrawal of a pin 57 from engagement with one of the openings 58, the turn table 56 can be given a rotary movement with respect to the gear 55 and the pin 57 re-inserted in another of said openings 58. Upon a rotation of the turn table 56 in this way through an angle of 90 degrees in one direction from the position as shown in Fig. 1, coupled with a suitable adjustment of the crank means longitudinally of the table 15, a line of marking such as that indicated by the numeral 102 will be produced. Upon an adjustment of the turn table 56 at an angle of 90 degrees in the opposite direction, coupled with an adjustment of the crank means again longitudinally of the table 15, a line of marking such as that indicated by the numeral 103 would be produced. The marking 103 is seen to correspond to that along which the strip of metal 104 is cut as shown in Fig. 9, so as to bring the seam of the pipe toward the right as shown in Fig. 10.

As is clearly shown in Figs. 3 and 4, the ring 51 is graduated thereabout, in the construction shown having a series of marks 105 in equally spaced relation adapted by reference to an index mark 106 at one side to indicate critical posi-

tions at which the turn table 56 and the ring 51 have been given a complete rotation or some aliquot part thereof. For ease of comparing the position of the index mark 106 with the marks 5 105, such index mark is placed on a block 107 rising to substantially the same level as that of the top face of the ring. By the use of the inter-related marks 105 and 106, the operator is 10 enabled to stop the movement of the pencil 50 at any desired critical point in the rotation of the turn table and to place a mark at the corresponding critical point along the line being 15 traced by the pencil, as for example, the middle point 108 of the line 109 as shown in solid lines in Fig. 1, such mark being applied by means of a punch or otherwise. Such mark 108 at a critical point on the pipe formed from the sheet of metal 101 can then be used as a reference point with respect to an inter-related critical point 20 on another pipe to be joined thereto so as to insure that the workman in making the joint between the two pieces of pipe by a welding process shall be enabled readily to position the pieces of pipe in the designed relation to each other.

25 As will be appreciated from a study of my improved mechanism, the line of marking 109 shown in solid lines in Fig. 1 is a typical sine curve, the axis of the abscissas represented by the line 110 extending transversely of the table 30 at right angles to the guide 25 and corresponding to the circumference of the pipe to be formed. At any point along the line 109 the ordinate from that point to the axis 110 is equal to the sine of the angle defined by the trans- 35 verse line passing through the axis of the turn table 56 and the line joining said axis with the center of the wrist pin in the position of said wrist pin corresponding to the point of the curve in question. The ordinates rise in value from 40 0 to 1, decrease to 0, decrease further to minus 1, and again increase to 0, during the successive four quarter rotations of the turn table.

45 While I prefer to employ the form of mechanism as shown in my drawings and as above described, it is to be understood that my invention is not limited to this precise form and arrangement except so far as the claims may be so limited by the prior art, it being understood that changes in the form and arrangement might 50 well be made without departing from my invention.

I claim:—

55 1. In a mechanism of the type described, the combination of a frame, a pencil, means comprising a crank rotatably mounted on a fixed axis on said frame for giving said pencil a simple harmonic movement between predetermined limits with respect to said frame, and other means mounted on said frame and operatively connected 60 with said crank for giving said pencil a movement at right angles to said first named movement at a rate of movement directly proportional to the rate of rotary movement of the crank.

65 2. In a mechanism of the type described, the combination of a frame, a member mounted on said frame so as to have free reciprocatory movement on said frame along a fixed straight path and held against swinging movement with respect to the frame, a second member mounted on said 70 first named member so as to have free reciprocatory movement with respect to said first named member along a fixed straight path at right angles to the movement of said first named member and held against swinging movement with respect to said first named member, a pencil car-

ried by said second member independently of said first named member, means for giving one of said members a stroke in one direction and a return stroke in the opposite direction, and means for giving the other member a cross stroke in one direction in timed relation to the two strokes of said first named member. 5

3. In a mechanism of the type described, the combination of a frame, a member mounted on said frame so as to have free reciprocatory movement on said frame along a fixed straight path and held against swinging movement with respect to the frame, a second member mounted on said first named member so as to have free reciprocatory movement with respect to said first named member along a fixed straight path at right angles to the movement of said first named member and held against swinging movement with respect to said first named member, a pencil carried by said second member, crank means for giving one of said members a stroke in one direction and a return stroke in the opposite direction comprising a simple harmonic movement, and means adapted during the period of said first mentioned two strokes to give the other member 25 a stroke in one direction at a rate of movement directly proportional to the rate of rotary movement of the crank means.

4. In a mechanism of the type described, the combination of a frame, a pencil, positively acting means comprising a rotary member adapted upon rotation to give said pencil a simple harmonic movement with respect to said frame in one direction, positively acting means for giving said pencil a movement at right angles with 35 respect to said first named movement, and positively acting connections between said two pencil moving means serving to cause said second mentioned moving means to move at a rate strictly proportional to the rate of rotary movement 40 of said rotary member.

5. In a mechanism of the type described, the combination of a frame, a bar extending across said frame, a member slidably mounted on said bar, an elongated member slidably mounted on 45 said first named member so as to move longitudinally of itself in a cross direction as compared with the movement of the first named member, a pencil mounted on said elongated member, means for giving one of said members a stroke 50 in one direction and a return stroke in the opposite direction, and means for giving the other member a cross stroke in one direction in timed relation to the movement of said first named member. 55

6. In a mechanism of the type described, the combination of a frame, crank means rotatably mounted on said frame, a member mounted on said frame so as to have a reciprocatory movement thereon and held against swinging movement with respect to the frame, means providing a sliding connection between said crank means and said member for effecting a reciprocatory movement of the member upon a rotary movement of said crank means, a second member slidably mounted on said frame so as to have a free movement in the direction of the reciprocatory movement of said first named member and also a free movement at right angles thereto and held against swinging movement with respect to the 70 frame, a pencil connected with said second member so as to move therewith, means providing a sliding connection between said first named member and said second member so as to give said second member and said pencil a reciprocatory 75

movement corresponding to the reciprocatory movement of said first named member while leaving the pencil free with respect to the movement at right angles, and other means for giving said second member and said pencil a movement at right angles to said reciprocatory movement and effective in direct proportion to the rotary movement of said crank.

7. In a mechanism of the type described the combination of a frame, crank means rotatably mounted on said frame, a member mounted on said frame so as to have a reciprocatory movement thereon and held against swinging movement with respect to the frame, means providing an operating groove along said member in engagement with said crank means for movement of the member by said crank, other means providing a second operating groove along said member parallel with said first named groove, a rod mounted on said frame and having sliding engagement with said second operating groove, means so as to be movable transversely of itself along said groove and movable longitudinally of itself with said first named member, means for holding said rod against swinging movement with respect to said frame, a pencil connected with said rod so as to move therewith, and means for giving said rod and pencil a movement transversely of the rod in timed relation to the reciprocatory movement of the rod by said crank means arranged so that said transverse movement of the rod is proportional to the rotary movement of the crank means.

8. In a mechanism of the type described, the combination of a frame, crank means rotatably mounted on said frame, a member mounted on said frame so as to have a reciprocatory movement thereon and held against swinging movement with respect to the frame, means providing a sliding connection between said crank means and said member for effecting a reciprocatory movement of the member upon a rotary movement of said crank means, a second member slidably mounted on said frame so as to have a free movement in the direction of the reciprocatory movement of said first named member and also a free movement at right angles thereto and held against swinging movement with respect to the frame, a pencil connected with said second member so as to move therewith, means providing a sliding connection between said first named member and said second member so as to give said second member and said pencil a reciprocatory movement corresponding to the reciprocatory movement of said first named member while leaving the pencil free with respect to the movement at right angles, and positively acting endless belt means extending across said frame and connected with said second member so as to give it a cross movement at right angles to said reciprocatory movement and also connected with said crank means for giving the crank means a rotary movement proportional to said cross movement of the pencil.

65 9. In a mechanism of the type described, the combination of a frame, a pencil, a guide, means for supporting said guide longitudinally of said frame at one side thereof, means mounted on said frame for giving said pencil a movement parallel with said guide, other means for giving said pencil a movement at right angles to said guide, one of said pencil moving means comprising in effect a crank for producing a simple harmonic movement of the pencil, and means for actuating said two pencil moving means in timed

relation to each other serving to keep the rotary movement of the crank means proportional to the movement of the pencil by the other pencil moving means.

10. In a mechanism of the type described, the combination of a frame, a pencil, a guide, means for supporting said guide longitudinally of said frame at one side thereof, means mounted on said frame for giving said pencil a movement parallel with said guide, other means for giving said pencil a movement at right angles to said guide, one of said pencil moving means comprising in effect a crank for producing a simple harmonic movement of the pencil, means for actuating said two pencil moving means in timed relation to each other serving to keep the rotary movement of the crank means proportional to the movement of the pencil by the other pencil moving means, and means for moving said guide transversely of itself serving to hold the guide against swinging movement with respect to the frame.

11. In a mechanism of the type described, the combination of a table, a frame mounted on said table and movable longitudinally thereof, a guide on said table underneath said frame in parallel position with respect to the direction of movement of the frame, means for moving said guide transversely of itself serving to hold the guide against swinging movement with respect to the frame, a pencil, means mounted on said frame for giving said pencil a movement parallel with said guide, other means for giving said pencil a movement transversely of the guide at right angles thereto, one of said pencil moving means comprising in effect a crank for producing a simple harmonic movement of the pencil, and means for actuating said two pencil moving means in timed relation to each other serving to keep the rotary movement of the crank means proportional to the movement of the pencil by the other pencil moving means.

12. In a mechanism of the type described, the combination of a frame, a bar adjustably mounted on said frame, a member slidably mounted on said bar, a second bar adapted to swing about a vertical axis on said frame and adapted upon a swinging movement to cause said member to move along said first named bar, means for adjusting said first named bar toward and from said vertical axis for changing the length of the stroke of said member as produced by a full stroke movement of said second bar, a pencil, operative connections between said pencil and said member for causing the pencil to move back and forth with said member, and other means for giving said pencil a movement at right angles with respect to said first named movement in timed relation thereto.

13. In a mechanism of the type described, the combination of a frame, a bar adjustably mounted on said frame, a member slidably mounted on said bar, a second bar adapted to swing about a vertical axis on said frame and adapted upon a swinging movement to cause said member to move along said first named bar, means for adjusting said first named bar toward and from said vertical axis for changing the length of the stroke of said member as produced by a full stroke movement of said second bar, a pencil, operative connections between said pencil and said member for causing the pencil to move back and forth with said member, and crank means for giving said pencil a movement at right angles with respect to said first named movement arranged so that said first named movement is proportional to the rotary movement of said crank means.

14. In a mechanism of the type described, the combination of a frame, a bar adjustably mounted on said frame, a member slidably mounted on said bar, a second bar adapted to swing about a vertical axis on said frame and adapted upon a swinging movement to cause said member to move along said first named bar, means for adjusting said first named bar toward and from said vertical axis for changing the length of the stroke of said member as produced by a full stroke movement of said second bar, a rod slidably mounted on said member and held against swinging movement with respect thereto, a pencil carried by said rod so as to be moved back and forth with said member, and crank means for giving said rod a movement longitudinally of itself with respect to said member and arranged so that the movement of said member along said first named bar is proportional to the rotary movement of said crank means.

15. In a mechanism of the type described, the combination of a frame, a bar adjustably mounted on said frame, a member slidably mounted on said bar, a second bar adapted to swing about a vertical axis on said frame and adapted upon a swinging movement to cause said member to move along said first named bar, means for adjusting said first named bar toward and from said vertical axis for changing the length of the stroke of said member as produced by a full stroke movement of said second bar, means for holding said first named bar against swinging movement with respect to said frame as it is adjusted toward and from said vertical axis, a pencil, operative connections between said pencil and said member for causing the pencil to move back and forth with said member, and crank means for giving said pencil a movement at right angles with respect to said first named movement arranged so that said first named movement is kept proportional to the rotary movement of said crank means.

16. In a mechanism of the type described, the combination of a frame, a bar mounted in fixed position on said frame, a second bar mounted on said frame in parallel position with respect to said first named bar, a member slidably mounted on said second bar, a third bar adapted to swing about a vertical axis on said frame and pivotally and slidably connected with said member for moving the member along said second bar upon a swinging movement of said third bar, a second member slidably mounted on said first named bar and having a pivotal connection with said third bar, means for adjusting said second bar toward and from said vertical axis for changing the length of the stroke of said first named member produced by a full stroke movement of said third bar, a pencil, operative connections between said pencil and said first named member for causing the pencil to move back and forth with said first named member, and other means for giving said pencil a movement at right angles with respect to said first named movement in timed relation thereto.

17. In a mechanism of the type described, the combination of a frame, a bar mounted in fixed position on said frame, a second bar mounted on said frame in parallel position with respect to said first named bar, a member slidably mounted on said second bar, a third bar adapted to swing about a vertical axis on said frame and pivotally and slidably connected with said member for moving the member along said second bar upon a swinging movement of said third

bar, a second member slidably mounted on said first named bar and having a pivotal connection with said third bar, means for adjusting said second bar toward and from said vertical axis for changing the length of the stroke of said first named member produced by a full stroke movement of said third bar, a pencil, operative connections between said pencil and said first named member for causing the pencil to move back and forth with said first named member, 10 crank means for giving said pencil a movement at right angles with respect to said first named movement, and means operatively connecting said second member and said crank means serving to revolve the crank means and to move 15 said second member for swinging said third bar in direct proportion to the rotary movement of the crank means.

18. In a mechanism of the type described, the combination of a frame, a pencil, means comprising a crank rotatably mounted on a fixed axis on said frame for giving said pencil a simple harmonic movement with respect to said frame, a sprocket gear rotatable with said crank, a sprocket chain operating on said sprocket gear 25 for rotating the crank, means for driving said chain alternatively in opposite directions, and means connected with said chain and actuated thereby for giving said pencil a movement at right angles to said first named movement at a 30 rate directly proportional to the rate of rotary movement of the crank.

19. In a mechanism of the type described, the combination of a frame, a bar mounted in fixed position on said frame, a second bar mounted 35 on said frame in parallel position with respect to said first named bar, a member slidably mounted on said second bar, a third bar adapted to swing about a vertical axis on said frame and pivotally and slidably connected with said member for moving the member along said second bar upon a swinging movement of said third bar, a second member slidably mounted on said first named bar and having a pivotal connection with said third bar, means for adjusting said second 45 bar toward and from said vertical axis for changing the length of the stroke of said first named member produced by a full stroke movement of said third bar, a pencil, operative connections between said pencil and said first named member 50 for causing the pencil to move back and forth with said first named member, crank means for giving said pencil a movement at right angles with respect to said first named movement, a sprocket gear rotatable with said crank means, 55 an endless chain operating on said sprocket gear and connected with said second slide member for swinging said third bar, and means for driving said chain alternatively in opposite directions.

20. In a mechanism of the type described, the combination of a frame, a pencil, means comprising a crank mounted on said frame for giving said pencil a stroke in one direction, other means mounted on said frame for giving said pencil a movement at right angles to said first named movement; means for adjusting the length of said second named pencil movement corresponding to the circumference of the pipe to be formed 70 means for adjusting the effective length of the crank for producing the desired angular formation for the diameter of pipe being formed, and means for actuating said two pencil moving means so as to keep the second named movement 75

of the pencil proportional to the rotary movement of the crank means.

21. In a mechanism for laying out lines of cutting for forming angular pipe joints, the combination of a frame for supporting the piece to be cut, a pencil, means mounted on said frame for giving said pencil and said piece to be cut a relative movement in the direction corresponding to the circumference of the finished pipe and corresponding in extent to said circumference, a member rotatably mounted on said frame, a wrist pin mounted on said rotary member and movable across said member diametrically thereof, a lever pivotally mounted on said rotary member on an axis adjustable toward and from the axis of the member so that said lever is adapted to extend across the path of movement of the wrist pin at any desired point along said path, means for giving said wrist pin a sliding connection with said lever whereby the position of the wrist pin is controlled by the point at which said lever crosses said path, means for holding said lever in a selected adjustment on said rotary member, and means actuated by the movement of said wrist pin upon the rotation of said rotary member for giving said pencil a movement with respect to said piece to be cut in the direction corresponding to the length of the pipe.
22. In a mechanism for laying out lines of cutting for forming angular pipe joints, the combination of a frame for supporting the piece to be cut, a pencil, means mounted on said frame for giving said pencil and said piece to be cut a relative movement in the direction corresponding to the circumference of the finished pipe and corresponding in extent to said circumference, a member rotatably mounted on said frame, a wrist pin mounted on said rotary member and movable across said member diametrically thereof, a lever pivotally mounted on said rotary member on an axis adjustable toward and from the axis of the rotary member along a path at right angles to the path of movement of said wrist pin and arranged so that in its various adjusted positions it extends at an angle to said path, means for giving said wrist pin a sliding connection with said lever whereby a swinging movement of the lever serves to adjust the wrist pin along said diametrical path, means for holding said lever in a selected adjustment on said rotatable member, and means actuated by the movement of said wrist pin upon the rotation of said rotary member for giving said pencil a movement with respect to said piece to be cut in the direction corresponding to the length of the pipe.

23. In a mechanism for laying out lines of cutting for forming angular pipe joints, the combination of a frame for supporting the piece to be cut, a pencil, means mounted on said frame for giving said pencil and said piece to be cut a relative movement in the direction corresponding to the circumference of the finished pipe and corresponding in extent to said circumference, a member rotatably mounted on said frame, a wrist pin mounted on said rotary member and movable across said member diametrically thereof, a lever pivotally mounted on said rotary member on an axis adjustable toward and from the axis of the rotary member along a path at right angles to the path of movement of said wrist pin and arranged so that in its various adjusted positions it extends at an angle to said path, means for giving said wrist pin a sliding

connection with said lever arranged so that as the wrist pin is adjusted longitudinally of the lever the axis of the pin remains constantly in a line passing through the axis of the lever and whereby a swinging movement of the lever serves to adjust the wrist pin along said diametrical path, means for holding said lever in a predetermined adjustment on said rotary member, graduated scale means for showing the angular adjustment from the perpendicular line leading from the axis of the lever to the diametrical path of said wrist pin, and means actuated by the movement of said wrist pin upon the rotation of said rotary member for giving said pencil a movement with respect to said piece to be cut in the direction corresponding to the length of the pipe.

24. In a mechanism for laying out lines of cutting for forming angular pipe joints, the combination of a frame for supporting the piece to be cut, a pencil, means mounted on said frame for giving said pencil and said piece to be cut a relative movement in the direction corresponding to the circumference of the finished pipe and corresponding in extent to said circumference, a member rotatably mounted on said frame and having a slideway thereacross in diametrical position, a wrist pin slidably mounted on said slideway, a lever pivotally mounted on said rotary member on an axis adjustable toward and from the axis of the rotary member along a path at right angles to said slideway, said lever having a slideway longitudinally thereof also having sliding engagement with said wrist pin and arranged so that as the wrist pin is adjusted along said lever the center of the wrist pin travels on a line passing through the axis of the lever, means for holding said lever in a selected adjustment on said rotary member, and means actuated by the movement of said wrist pin upon the rotation of said rotary member for giving said pencil a movement with respect to said piece to be cut in the direction corresponding to the length of the pipe.

25. In a mechanism for laying out lines of cutting for forming angular pipe joints, the combination of a frame for supporting the piece to be cut, a pencil, means mounted on said frame for giving said pencil and said piece to be cut a relative movement in the direction corresponding to the circumference of the finished pipe and corresponding in extent to said circumference, a member rotatably mounted on said frame and having a slideway thereacross in diametrical position and a second slideway arranged radially at right angles to said first named slideway, a wrist pin slidably mounted in said first named slideway, a slide block slidably mounted in said second named slideway, a lever pivotally mounted on said slide block and arranged to be swung across said first named slideway at an angle thereto, means for clamping said slide block releasably in adjusted position along said second slideway, said lever being provided with a slideway longitudinally thereof within which said wrist pin is slidably mounted and arranged so that as the wrist pin is adjusted along said lever the center of the wrist pin travels on a line passing through the axis of said lever, means for clamping said lever in a selected angular adjustment with respect to said rotary member, and means actuated by the movement of said wrist pin upon rotation of said rotary member for giving said pencil a movement with respect to said piece to be cut in

the direction corresponding to the length of the pipe.

26. In a mechanism for laying out lines of cutting for forming angular pipe joints, the combination of a frame for supporting the piece to be cut, a pencil, means mounted on said frame for giving said pencil and said piece to be cut a relative movement in the direction corresponding to the circumference of the finished pipe and corresponding in extent to said circumference, a member rotatably mounted on said frame and having a slideway thereacross in diametrical position and a second slideway arranged radially at right angles to said first named slideway, a wrist pin slidably mounted in said first named slideway, a slide block slidably mounted in said second named slideway, a lever pivotally mounted on said slide block and arranged to be swung across said first named slideway at an angle thereto, means for clamping said slide block releasably in adjusted position along said second slideway, said lever being provided with a slideway longitudinally thereof within which said wrist pin is slidably mounted and arranged so that as the wrist pin is adjusted along said lever the center of the wrist pin travels on a line passing through the axis of said lever, means for clamping said lever in a selected angular adjustment with respect to said rotary member graduated scale means for showing the distance by which the axis of said lever is separated from the axis of said rotary member in the various adjustments of the lever on the rotary member, other graduated scale means for showing the angular adjustment of said lever with respect to said first named slideway, and means actuated by the movement of said wrist pin upon rotation of said rotary member for giving said pencil a movement with respect to said piece to be cut in the direction corresponding to the length of the pipe.

27. In a mechanism of the type described, the combination of a frame, a pencil, means comprising a crank mounted on said frame for giving

said pencil a simple harmonic movement between predetermined limits, other means mounted on said frame and operatively connected with said crank for giving said pencil a movement at right angles to said first named movement and proportional to the rotary movement of the crank, and index means for indicating critical positions of said crank at which predetermined aliquot parts of a complete rotation have been effected.

28. In a mechanism of the type described, the combination of a frame, a ring revolvably mounted on said frame, a pencil, a wrist pin adjustably mounted with respect to said ring comprising an adjustable crank, means actuated by said crank for giving said pencil a stroke and a return stroke between predetermined limits, other means mounted on said frame for giving said pencil a movement at right angles to said first named movement, means for actuating said two pencil moving means so as to keep the second named pencil movement proportional to the rotary movement of the crank, an index mark on said frame adjacent to said ring, and a series of marks in equally spaced relation about said ring adapted by reference to said index mark to indicate successive critical positions of said crank corresponding to predetermined aliquot parts of a complete rotation of the crank.

29. In a mechanism of the type described, the combination of a frame, a pencil, means comprising a crank mounted on said frame for giving said pencil a simple harmonic movement between predetermined limits, other means mounted on said frame and operatively connected with said crank for giving said pencil a movement at right angles to said first named movement and proportional to the rotary movement of the crank, and means for adjusting the angular position of the crank with respect to the means for causing said second named pencil movement for regulating the position of the seam in the finished pipe.

ALFRED F. KRUMHOLZ.
